(57) **CLAIM**

The ornamental design for an electric actuator as shown and described.

DESCRIPTION

FIG. 1 is a front, top right perspective view of an electric actuator according to a first embodiment;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a front, top left perspective view thereof;

FIG. 8 is a front, top right perspective view of the electric actuator according to a second embodiment;

FIG. 9 is a front elevation view thereof of the claimed design of FIG. 8;

FIG. 10 is a rear elevation view thereof;

FIG. 11 is a left side elevation view thereof;

FIG. 12 is a right side elevation view thereof;

FIG. 13 is a top plan view thereof;

FIG. 14 is a front, top left perspective view thereof;

FIG. 15 is a front, top right perspective view of the electric actuator according to a third embodiment;

FIG. 16 is a front elevation view thereof;

FIG. 17 is a rear elevation view thereof;

FIG. 18 is a left side elevation view thereof;

FIG. 19 is a right side elevation view thereof;

FIG. 20 is a top plan view thereof; and,

FIG. 21 is a front, top left perspective view thereof.

The broken lines depict portions of the electric actuator that form no part of the claimed design.
